[57] CLAIM

The ornamental design for the dental syringe, substantially as shown and described.

DESCRIPTION

FIG. 1 is a perspective view of the dental syringe showing a new design.

FIG. 2 is a left side view thereof.

FIG. 3 is a right side view thereof.

FIG. 4 is a top view thereof.

FIG. 5 is a bottom view thereof.

FIG. 6 is a front view thereof.

FIG. 7 is a rear view thereof.

FIG. 8 is a fragmentary perspective view of a second embodiment of my design;

FIG. 9 is a fragmentary perspective view of a third embodiment of my new design;

FIG. 10 is a fragmentary perspective view of a fourth embodiment of my new design.

The dental syringe is fragmentarily shown in FIGS. 8, 9 and 10 for convenience of illustration, it being understood that the injection gun in the second, third, and fourth embodiments is identical to that of the first embodiment.

FIG. 1

FIG. 2

FIG. 7

FIG. 8

FIG. 9

FIG. 10
